PUMP

Harold Neibert, Davenport, Iowa, assignor to
Micro-Westco, Inc., Bettendorf, Iowa, a corpora-
tion of Delaware

Application January 5, 1939, Serial No. 249,461

3 Claims. (Cl. 103—96)

This invention relates to improvements in pumps of the type having a rotary impeller with peripheral buckets which engage the liquid to be pumped in a pressure-developing channel.

More specifically, it relates to improvements in pumps of this character wherein the pressure-developing channel is formed by a pair of annular rings, which may be removed and replaced when it is desired to alter the performance or capacity of the pump, or which may be removed for any purpose.

After a period of operation of these liquid pumps the removable rings frequently stick tightly in the housing and it is very difficult to effect their removal. It is, therefore, an object of this invention to provide liquid pumps wherein the annular rings which cooperatively form the pressure-developing channel may be easily removed from the pump housing after the pump has been in operation for a considerable period.

Other objects will become apparent from the following detailed description of suitable embodiments of the invention made in connection with the accompanying drawings, in which

Figure 1 is an end elevation, partly in section, of a rotary impeller type pump embodying this invention;

Fig. 2 is a partial section of the pump on the line 2—2 of Fig. 1;

Fig. 3 is an end elevation of the housing of the pump illustrated in Fig. 1 with the cover plate removed;

Fig. 4 is an enlarged fragmentary sectional view showing a method for locking the annular pressure channel defining rings in the housing;

Fig. 5 is an end elevation, partly in section, of a rotary impeller type pump embodying a modification of my invention;

Fig. 6 is an end elevation, partly in section, of one of the annular rings;

Fig. 7 is an end elevation, partly in section, of another annular ring which cooperates with that shown in Fig. 6;

Fig. 8 is a side elevation of the ring shown in Fig. 6, looking in the direction of the arrows 8—8 of Fig. 6;

Fig. 9 is a side elevation of the ring shown in Fig. 7, looking in the direction of the arrows 9—9 in Fig. 7.

Referring more particularly to the drawings, in which like parts are identified by like numerals of reference throughout the several views, the pump comprises a rotary impeller 1, usually of relatively flat, disklike form, and provided with a plurality of marginal buckets 2, formed near

its peripheral edge. A set of buckets is shown as formed on each side of the rotor or impeller 1 and separated by a circumferentially extending web 3. The individual buckets in each set are separated from one another by the radial webs 4.

The impeller is secured on a shaft 5 and is disposed in the pump chamber 6, which is formed by the pump housing or casing 7 and a cover 8. It is driven by a motor, not shown, and the shaft is preferably carried in journals externally of the chamber 6.

The annular rings 9 and 10 are received in the pump chamber 6 and cooperatively define a pressure developing channel 11 which surrounds the peripheral edge of the impeller, so that the buckets move through the channel as the impeller rotates. The channel is substantially annular and is provided with an inlet 13 and an outlet 12. The inlet communicates with an intake passage 16 formed in a boss 17 of the housing 7, and the outlet communicates with the outlet passage 14 in the boss 15; also in the casing 7 and adjacent the boss 17. Each of the bosses 17 and 15 is suitably threaded to receive the intake and discharge pipes 19 and 18, respectively.

Between the inlet 13 and the outlet 12 the rings 9 and 10 closely surround the impeller edge, so that, during the operation of the pump, liquid flowing through the pressure developing channel is directed through the outlet 12. This closely fitting part of the rings is referred to as the stop and is indicated by the numeral 20.

Radially inward from the channel 11, the rings 9 and 10 are formed with annular sealing ribs 21 and 22, respectively, which have a running fit with the impeller 1 and prevent radial flow of the liquid into and out of the channel 11 from the center of the pump chamber 6. The rings 9 and 10 have circumferential ribs 23 and 24, respectively, which meet at the parting line 25 and cooperatively form the pressure developing channel. The ribs 23 and 24, of course, do not extend across the inlet 13 and the outlet 12, thereby permitting the ingress and egress of the liquid to and from the channel 11. In the region of the stop 20 the portion 26 of the rib 24 extends to a position closely adjacent the periphery of the impeller 1 and has a running fit therewith to cooperate with the stop 20 and the portion 27 of the rib 23 in directing liquid through the outlet 12. In the vicinity of the outlet 12 and the inlet 13, the rings 9 and 10 make good contact with the pump housing 7. To insure

against leakage the external peripheries of the rings 9 and 10 may be coated with paint, or other sealing material, when the pump is being assembled.

On account of hardening of the paint, corrosion, etc., these rings frequently stick in the pump housing, so that it is very difficult to remove them. According to this invention the rings 9 and 10 are forced tightly against the region or contact area 28, forming a seal between the inlet 13 and the outlet 12 from the pump chamber 6. The rings 9 and 10 are forced against the contact area 28 by suitable clamping means, which may be the set screws 29 and 30. The region or area 28 may extend beyond the region of the stop, but should not cover more than one-half of the internal periphery of the housing 7. The extent of the region or contact area is determined by the extent of the relieved portion 32 of the housing 7 and need not extend angularly more than the distance to effect a good seal, which generally is a slight distance beyond the inlet and outlet port areas.

Consequently, when rings 9 and 10 with circular peripheries are used the casing should be relieved around an inner circumference up to the point where it is desired to maintain contact between the rings and casing.

In Figs. 8 and 9 a modification of the invention is shown in which rings 9a and 10a are formed with relieved portions 34 and 35, and portions 31, which contact with the inner face 28 of the casing section to form the sealed region or portion.

The rings 9 and 10 preferably carry an aligning means, such as a V-groove 33, adapted to receive the movable clamping means 29 and 30, so that the inlet 13 and the outlet 12 will always be assembled adjacent the inlet and outlet passages 16 and 14, respectively. When the movable clamping means 29 and 30 are removed or loosened, the annular rings 9 and 10 are movable in the housing in a plane perpendicular to the axis of the pump shaft 5. In order to prevent binding between the impeller 1 and the housing 7 when the ring 9 is moved radially away from the contact surface, the portion 27 of the rib 23 is made so that it cannot come in contact with the impeller upon the slight radial motion. This may be accomplished by making the portion 27, or, if desired, all of rib 23, so that it does not extend sufficiently to intersect any plane which is perpendicular to the shaft, and which passes through the radial webs 4. The portion 26 of the rib 24 and the rib 24 of the annular ring 10 are extended to meet the portion 27 and the rib 23, respectively. Thus the portion 26, and, if desired, all of the rib 24, is made to extend entirely over the impeller 1.

When disassembling the pump, the set screw 29 is loosened and the annular ring 9 may be removed radially from the contact area 28 without interference occurring between the impeller and the portion 27. The impeller is next removed and, after loosening the clamping screw 30, the ring 10 may then be removed laterally from the bearing surface and withdrawn from the housing 7.

The depth of the relieved portions of the housing or rings, as the case may be, should preferably be sufficiently large to enable sediment or corrosion to be removed from between the annular rings and the housing. However, distances

in the order of $\frac{1}{8}$ " are usually sufficient. The rings 9 and 10 connect with the housing in the vicinity of the inlet and outlet 13 and 12, so as to cooperate with the inlet and outlet passages 16 and 14 and form continuous passages for the ingress and egress of fluid.

It will thus be seen that I have provided a form of pump in which the rings and pump casing may be readily separated, even after operation for long periods of time, when the rings and casing may very tightly adhere, due to hardening of the paint or other sealing means originally applied, as well as the collection of sediment and corrosion in this region.

Various modifications of the invention, which readily occur from a study of the foregoing disclosure and the illustrations in the drawings, are contemplated and intended to be included within the scope of the appended claims.

What I claim is:

1. In a rotary pump of the turbine type, a casing, annular rings disposed in the casing and having portions which cooperatively define a pressure developing channel, an impeller having marginal buckets mounted for rotation through the channel, an inlet and an outlet to the channel through the rings and casing, an area of contact for portions of the rings and the casing surrounding the inlet and outlet, said area extending over not more than half the internal periphery of the casing, means for securely holding the rings and casing together throughout the contact area, and means for releasing the holding means.

2. In a rotary pump of the turbine type, annular rings disposed in the casing and having portions which cooperatively define a pressure developing channel, an impeller having marginal buckets mounted for rotation through said channel, an inlet and an outlet for said channel through the rings and casing, stop means disposed between the inlet and the outlet and closely fitting the impeller to aid in directing liquid through the outlet, said stop means including portions which fit closely adjacent the periphery of the impeller, said portions being carried by the ring which is normally last removed on disassembly of the pump to provide facile removal of said rings without danger or injury to the impeller, an area of contact for the rings and the casing surrounding the inlet and the outlet to provide a seal, said area of contact extending over not more than half the internal periphery of the casing, means for holding the rings and the casing securely together throughout the contact area, and means for releasing the holding means.

3. In a rotary pump, a casing, removable annular rings disposed in the casing and having portions which cooperatively define a pressure developing channel, an impeller mounted for rotation through said channel, an outlet from the channel through the rings and the casing, an area of contact for portions of the rings and casing surrounding the outlet to provide an effective seal for the outlet, said area extending over less than half the internal periphery of the casing to permit facile removal of the rings, means for securely holding the rings and casing together throughout the contact area, and means for releasing the holding means.

HAROLD NEIBERT
